COMBINATION HOLDER AND PACKAGE FOR SUPPOSITORIES OR THE LIKE

Charles Nicolle, 54 Ave. Foch, Paris, France

Filed Jan. 27, 1960, Ser. No. 59,185

Term of patent 14 years

(Cl. D58—2)

Fig. 1 is a perspective view of a combination holder and package for suppositories or the like embodying my new design;

Fig. 2 is a side elevational view thereof; and

Fig. 3 is an enlarged fragmentary front elevational view illustrating one of the holding compartments.

The rear and side, not shown, are the same as the respective front and side views shown.

I claim:

The ornamental design for a combination holder and package for suppositories or the like, as shown and described.
